UNITED STATES PATENT OFFICE.

CHARLES O. TUCKER, OF HUTCHINSON, KANSAS.

TONE REGULATOR.

Application filed November 2, 1921. Serial No. 512,235.

To all whom it may concern:

Be it known that I, CHARLES O. TUCKER, citizen of the United States, residing at Hutchinson, in the county of Reno and State 5 of Kansas, have invented certain new and useful Improvements in Tone Regulators, of which the following is a specification.

This invention relates to phonograph attachments and more particularly to a novel 10 and improved means for modifying or regulating the volume of tone without the necessity of using different kinds of needles.

The primary object of the invention is the 15 construction of a tone regulating or modifying attachment for phonographs, wherein pressure may be exerted on the needle to a more or less degree so that the varying resistances produced will correspondingly change the vibrations to effect the modified 20 tones desired.

One of the objects of the invention is the provision of a sound modifying attachment 25 of the class above set forth, wherein the volume of tone may be regulated while the machine is playing.

A still further object of the invention is the construction of a sound modifying attachment adapted for easy installation on practically any type of sound box and one 30 in which the parts are extremely simple in construction, easily assembled, rigid and durable, highly efficient in operation, practical and capable of being manufactured at a very 35 low cost, whereby its commercial possibilities are greatly enhanced.

This invention will be best understood from a consideration of the following detailed description taken in connection with the accompanying drawing forming a part 40 of this specification, with the understanding, however, that the invention is not confined to any strict conformity with the showing in the drawing, but may be changed and modified so long as such changes and modifications 45 mark no material departure from the salient features of the invention as expressed in the appended claims.

I attain these objects and others in the accompanying drawings, wherein:

50 Figure 1 is a face view of the sound box, provided with my attachment.

Figure 2 is a side view of the sound box, provided with the attachment, parts being shown in section.

55 Figure 3 is a detail view, showing the adjusting means for the rod.

Figure 4 is a detail view of the bent portion of the rod and the pressure contacting surface therein.

Figure 5 is a section view, taken on the line 5-5 of Figure 4.

Referring now to the drawings wherein like reference characters designate corresponding parts throughout the several views, 5 designates the usual sound box of a sound reproducing machine and 6 the diaphragm, while 7 designates the stylus arm or stylus supporting member mounted in the usual manner and which transfers the vibrations of the record to the diaphragm 6, above referred to. These parts are of course, common to practically all types of phonographs and form no part of the present invention.

The sound box 5 is provided with diametrically opposed ears 8, 9, on its outer periphery, which rotatably supports the transversely extending rod 10 journaled for rocking movement therein. The said ear 9 is provided with teeth 10 thereon for engagement with the pin 11, extending inwardly from the bent arm 12 on the outer end of the rod 10, whereby the said rod may be manipulated to vary the degree of tone desired.

The said ear 9 has also connected thereto one end 13 of a spring 14, wound about said rod and a similar spring 15 connected to the rod and to the ear 8 is provided on the opposite side of the centrally disposed bent portion 16, which is adapted to engage the bent or inwardly extending end 17 of the stylus connected to the diaphragm 6. In order to effect a sensitive variation in the tone and avoid undue vibrations, I have provided a felt or cork contacting surface 18 positioned beneath the humped or bent portion 16 of the rod, whereby when pressure is produced on the stylus the metal of the bent portion will be prevented from vibrating with the stylus arm 7.

By reason of this construction it will be readily seen that as the rod 10 is rocked to effect the various pressures on the stylus arm 7, due to the varying vibrations resulting a different tone may be produced and that the same may be effected while the machine is playing and of course, without the necessity of changing the needle. The springs 14 and 15, of course, tend to keep the rod, above referred to, out of contact with the inwardly bent portion of the stylus arm and this position will permit the needle to produce the loudest tone. However, as the rod 10 is

rocked and moved to the various positions to be held by the teeth 10, it will be seen that different pressures are exerted on the stylus arm and of course the greater the resistance the weaker the tones will be produced.

The device is such that the extreme simplicity thereof permits the same to be easily attached to practically any type of sound box without injury to the same, nor would the diaphragm 6 be in any way affected by the season of the attachment. Furthermore the device does not in any way otherwise affect the tone of the sound box when the device is not in use and thus the attachment is highly efficient in operation when various tones are desired to obtain the best result in playing selections wherein the volume of tone must be regulated in order to bring out the variations in the tone desired.

In the accompanying drawings, I have illustrated my invention embodied in one form by way of example, and which in practice has been found to be highly satisfactory in obtaining the desired results. It will be obvious however, that other embodiments may be adopted, and that various changes in the details of construction may be resorted to by those skilled in the art without departing from the spirit and scope of the invention. It is furthermore understood that the invention is not necessarily limited or restricted to the precise elements shown except in so far as such limitations are specified in the subject matter being claimed.

Having thus described and illustrated my invention, what I claim as new and desire to secure by Letters Patent is:

1. The combination with a sound box, a diaphragm and stylus carrying member, of diametrically opposed attaching members formed on the outer periphery of the sound box, teeth formed on one of said attaching members, a transversely extending rod having a bent end adjustable on said teeth and

resilient means secured on said rod whereby the contacting pressure with the stylus carrying member may be varied to regulate the volume of tone.

2. The combination with a sound box, a diaphragm and stylus carrying member, of a transversely extending rod operatively supported on the sound box, said rod having an intermediate bent portion for contacting pressure engagement with the stylus carrying member and means for retaining said rod in various positions whereby the pressure between the bent portion of the rod and the stylus carrying member will permit the volume of tone to be modified.

3. The combination with a sound box, a diaphragm and stylus carrying member, of a transversely extending rod on the sound box, said rod having an intermediate bent portion for contacting pressure engagement with the stylus carrying member and a retaining arm on one end of said rod for adjustably securing the same in various positions, whereby the volume of tone may be regulated.

4. The combination with a sound box, a diaphragm and stylus carrying member, of attaching members formed on the sound box, a transversely extending rod operatively supported by said attaching members, resilient means secured to said attaching members and to the said rod for retaining the same out of engagement with the stylus carrying member, a bent arm formed on said rod for rocking the same, said rod having an intermediate bent portion disposed between the resilient members for contacting engagement with the stylus carrying arm.

In testimony whereof I affix my signature in presence of two witnesses.

CHARLES O. TUCKER.
